Primary Examiner — Michael A. Pratt*(74) Attorney, Agent, or Firm* — Roland R. Schindler, II; Brian Shaw; Harter Secrest & Emory, LPP(57) **CLAIM**

The ornamental design for a firearm mount with embedded laser sight, as shown and described herein.

DESCRIPTION

FIG. 1 is a bottom, front, left side isometric view of the laser aiming device in accordance with my new design.

FIG. 2 is a bottom, front, right side isometric view of the embodiment of FIG. 1, with a battery door removed.

FIG. 3 is a top, back, left side isometric view of the embodiment of FIG. 1; and,

FIG. 4 is a top, back, right side isometric view of the embodiment of FIG. 1, with a battery door shown separated therefrom.

The dashed lines in the figures do not form any part of the design sought to be patented.

1 Claim, 4 Drawing Sheets
